Patented May 13, 1919.

UNITED STATES PATENT OFFICE.

CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

NON-INDUCTIVE INTERFERENCE SYSTEM.

1,303,281.

Specification of Letters Patent.

Patented May 13, 1919.

Application filed September 28, 1917. Serial No. 193,725.

To all whom it may concern:

Be it known that I, CHARLES LE G. FORTESCUE, a subject of the King of Great Britain, and a resident of Pittsburgh, in the 5 county of Allegheny and State of Pennsylvania, have invented a new and useful Improvement in Non-Inductive Interference Systems, of which the following is a specification.

10 My invention relates to electrical distributing systems and it has special relation to alternating-current systems in which novel means are employed for controlling the power-factors of the load currents obtain- 15 ing therein.

More particularly, my invention relates to distributing systems that are supplied with electrical energy from a plurality of spaced sub-stations and upon which variable loads 20 obtain at points intermediate the sub-stations. The currents occasioned by these variable loads may possibly change in value, as well as possess varying power factors.

My invention, in the present instance, is 25 shown applied to an alternating-current railway system that is paralleled for longer or shorter distances by an intelligence-transmission circuit, such as a telephone or telegraph circuit. As a consequence of 30 constructing a railway system in accordance with my invention, inductive disturbances that are usually prevalent in circuits adjacent to an alternating-current railway system fed from a plurality of spaced sub-sta- 35 tions that severally deliver power currents in both directions, may be sufficiently minimized to insure against the railway system interfering, to any appreciable degree, with the normal operation of the adjacent cir- 40 cuits.

Another advantage accruing from the use of my invention is that the power-factor of a power circuit fed from a power-transmission system may be controlled independ- 45 ently of the power-transmission system and maintained at any predetermined value, irrespective of the character of the load obtain- 50 ing in the power circuit.

In alternating-current railway systems 55 comprising two or more spaced sub-stations that furnish electrical energy to a plurality of loads fed from a common trolley con-

ductor, it is difficult to protect an adjacent telephone circuit against inductive disturbances because the currents supplied to the 55 loads are continually varying in amount, as well as in power-factor. It has been proposed to maintain the voltages impressed upon the railway circuit by the several sub-stations substantially equal to one another 60 in value. Under ordinary circumstances, this would insure the production of slight disturbing influences only, but, by reason of the different power-factors of the currents simultaneously delivered from the power 65 stations, the maintaining constant of the impressed voltages is not a sufficient precaution to minimize the inductive disturbances to a satisfactory degree. In addition, it is necessary to adjust the phases of the cur- 70 rents flowing in the railway circuit in opposite directions to an intermediate load point in order that the resulting inductive disturbances impressed upon the adjacent circuit may be substantially minimized. If the op- 75 positely-directed currents are not maintained substantially in phase opposition to each other, the resultant inductive effects may be sufficient to seriously interfere with the satisfactory operation of any circuit sub- 80 ject to the inductive disturbances that arise from the flow of power currents in the rail- 85 way system. It will be noted, therefore, that the value of the voltages impressed upon the power circuit should be controlled, as well as the phases of the power currents, in order to sufficiently minimize the inductive 90 disturbances that otherwise would be impressed upon an adjacent circuit. To the accomplishment of this result and other ob- 95 jects to be hereinafter disclosed, the present invention is directed.

For a better understanding of the nature and scope of my invention, reference may be had to the following description and the accompanying drawing; in which Figure 1 is a diagrammatic representation of a railway system embodying a form of my invention, and Fig. 2 is a vectorial diagram illustrating the mode of operation of the system 100 shown in Fig. 1.

Referring to Fig. 1, a railway circuit, constituting a trolley conductor 1 and a track 2, is furnished with power from a plu-

rality of spaced sub-stations, such as are indicated at 3 and 4. The substations 3 and 4 are shown as supplying load currents to an intermediate load vehicle 5. It is to be understood, of course, that each substation may furnish power-currents to loads intermediate the immediately adjacent substations, as well as loads of other characteristics at more remote points on the railway system. It is evident, also, that each substation may deliver power currents of different values and characteristics in both directions.

An intelligence-transmission conductor 6 is disposed adjacent to the trolley conductor 1 and the track 2, and is, therefore, under the inductive influences arising from the currents flowing in the railway circuit. For the purpose of illustration only, the telephone conductor 6 may be considered as being uniformly spaced from the trolley conductor 1 throughout its entire length. It will be understood, however, that my invention is effective in minimizing inductive disturbances whether or not the telephone conductor 6 is spaced uniformly from the trolley conductor 1 throughout its entire length.

The substations 3 and 4 are supplied with power delivered over phase 7 of a polyphase transmission circuit 8. I have shown the transmission circuit 8 as a two-phase circuit but my invention is not limited to a transmission circuit of this character, since any polyphase circuit may be transformed into a two-phase circuit wherein two electromotive forces displaced 90° in phase from each other may be obtained by many well-known methods, such, for instance, as a 40 T-transformer connection.

It is to be presumed that the sub-stations 3 and 4 are spaced considerable distances from each other, such distance depending upon the particular features embodied in, and the character of, the railway system. Again, the substations 3 and 4 are representative only of the many substations that may furnish power to the system, each substation being substantially a duplicate, so far as the electrical equipment is concerned, of the other substations. Therefore, I will describe my invention as applied to the substations 3 and 4 only, it being understood that the operation of the electrical equipment of the remaining substations is similar.

The substation 3 comprises a power transformer 9, the primary winding 10 of which is connected to the phase 7. A secondary winding 11 has its terminals 12 connected directly to the trolley conductor 1 and its terminal 13 connected, through the armature circuits of booster generators 14 and 15, a primary winding 16 of a current transformer 17 and a conductor 18, to the railway track 2. The booster generators 14 and

15 are single-phase commutator-type generators having their armatures mounted upon a common shaft 19 that is rotated by means of a synchronous alternating-current motor 20. The motor 20 is shown as a polyphase motor which is supplied with alternating-currents from the transmission circuit 8 through conductors 21.

An exciting winding 22 of the booster generator 14 has its terminals connected to 75 conducting segments 23 and 24 of a variable rheostat 25. The rheostat 25 comprises a continuous resistance element 26, two diametrically opposite points 27 and 28 thereof being connected through conductors 29 and 30, 80 respectively, to phase 7 of the transmission circuit 8. A rotatable contact-making element comprises two insulated conducting arms 32 and 33 that are adapted to bridge, respectively, the conducting segments 23 and 24 and accessible taps 34 and 35 of the resistor 26. The adjustable contact-making arm is rotated by means of a shaft 36 of a motor 38. The motor 38 is connected through a reversing switch 39 of a well-known type, 90 and conductors 40 to the phase 7.

It will be observed that the field winding 22 of the booster generator 14 is excited by an alternating-current delivered from the same phase 7 of the supply circuit as the power currents furnished to the railway system. As is well known, an alternating-current commutator-type generator generates an electromotive force that is in phase with the current flowing in its exciting winding. 100 Therefore, the voltage generated by the booster generator 14 may be in phase with the voltage of phase 7.

An exciting winding 41 of the booster generator 15 is likewise connected in circuit 105 with an adjustable rheostat 25^a. Diametrically opposite points 27^a and 28^a of this rheostat are, however, connected through leads 29^a and 30^a, respectively, to the phase 31. A reversing switch 39^a controls the direction of rotation of a motor 38^a which operates the contact-making arms of the adjustable rheostat 25^a.

Since the booster generator 15 is excited by an alternating-current delivered from the phase 31 of the two-phase supply circuit 8, and the booster generator 14 is supplied with an exciting current from the phase 7 of the two-phase supply circuit 8, the electromotive forces generated in the respective armature windings of the said two booster generators will be displaced 90° in phase from each other. These electromotive forces, in conjunction, serve to adjust the resultant electromotive force impressed upon the railway 125 circuit at the substation 3.

The direction of rotation of the motor 38 is controlled by means of a contact-making voltmeter 44 which comprises an electromagnet 45, having a movable core 46 that is 130

linked, at its upper end, to a pivoted arm 47. A spring 48 is so designed as to aid in balancing the weight of the core member 46 when a voltage of predetermined value is impressed upon a secondary winding 49 of a voltage transformer 50, the primary winding 51 of which is connected across the trolley conductor 1 and the track 2. The pivoted arm 47 is provided with a contact member 52 which may engage the one or the other of stationary contact members 53 and 54. When an abnormally high current is demanded of the substation 3, the voltage impressed upon the electromagnet 45 momentarily decreases, thereby permitting the pivoted arm 47 to effect engagement between the contact members 53 and 52. Likewise, when the voltage impressed upon the railway circuit exceeds the predetermined value, engagement is effected between contact members 52 and 54. The circuits established through the contact points 53 and 54 control the excitation of electromagnets 53^a and 54^a, respectively, of the reversing switch 39. In this manner, the direction of rotation, as well as the excitation of the motor 38, is controlled in accordance with the value of the voltage impressed upon the railway circuit by the substation 3.

30 A modified form of a power-factor relay, shown at 55, controls the excitation and direction of rotation of the motor 38^a in accordance with the phase displacement between the current furnished to the moving load 5 from the substation 3 and that furnished thereto from the substation 4. The power-factor relay 55 comprises a winding 56 which is supplied with current from a secondary winding 57 of the series transformer 17, the primary winding 16 of which, as hereinbefore stated, is connected in series circuit with the secondary winding 11 of the power transformer 9. The coil 56 is disposed upon a core 57 of magnetizable material. Fine-wire coils 58 and 59, mounted upon a common rotatable axis in the field created by the winding 56 and the core member 57, are subject to the restraining influence offered by a tensional element or coiled spring 60. The two coils 58 and 59 are connected in different branches of a circuit connected to a secondary winding 61 of a current transformer 62 which is located in the substation 4. A primary winding 61^a of the transformer 62 is connected in series circuit with one terminal 63 of a power-transformer 64 that is placed in the substation 4. The secondary winding 61 is connected to the coils 58 and 59 of the relay 55, placed in the substation 3, by means of pilot conductors 65 that serve to interconnect the spaced substations with each other. A non-inductive element 66 and an inductive element 67 are connected, respectively, in circuit with the coils 59 and 58 in order to obtain an operative quadrature-phase relationship between the currents flowing in the said two coils. A contact-making pointer 68, mounted upon the common axis of the coils 58 and 59, operates 70 to connect a conducting segment 69 to either a conducting segment 70 or a conducting segment 71, depending upon the nature of the interaction between the coil 56 and the conjoint action of the coils 58 and 59. When 75 the contact member 68 engages the one or the other of the contact segments 70 and 71, the reversing switch 39^a will be actuated, as hereinbefore explained in connection with the reversing switch 39^a, to properly 80 excite the motor 38^a.

Referring to the operation of the power-factor relay 55, the coil 56 is traversed by a current, the phase of which always bears a definite relation to that of the power current supplied by the substation 3 to the railway circuit. The coils 58 and 59 are traversed by currents having displaced phases, but which also bear a definite phase relation to the power current furnished by the 85 substation 4 to the railway circuit. As a result, the movable system comprising the coils 58 and 59 will take a position depending upon the phase displacement between the oppositely directed currents supplied to 90 the intermediate load 5 from the substations 3 and 4. The power-factor relay 55 is so adjusted that only when the power currents supplied from the substations 3 and 4 are in substantial phase opposition, the pointer 68 100 will occupy a zero position intermediate the conducting segments 70 and 71. When the phase relationship between said power currents depart from a substantial phase opposition, the contact-making pointer 68 will 105 engage the one or the other of the conducting segments 70 and 71 and, in this manner, control the direction of rotation of the motor 38^a.

It will be appreciated that the inductive 110 disturbances impressed upon the adjacent telephone circuit 6 must be substantially neutralized in order to permit satisfactory operation of the telephone circuit and, to this end, the electromotive forces induced in 115 the telephone conductor 6, by reason of the load currents flowing in opposite directions from the substations 3 and 4 to the intermediate load 5, must be substantially neutralized. Since the electromotive forces induced in the telephone conductor 6 are proportional to the ampere-miles on each side of the moving vehicle 5, it is necessary that the oppositely directed load currents traversing the trolley conductor 1 shall be inversely proportional to the length of the circuits intervening between the said substations and the load 5. To accomplish this, it is necessary that the voltages impressed 120 upon the railway circuit by the substations 125 130

be maintained substantially constant and equal in value, irrespective of the position of the moving vehicle 5 and the power requirements thereof. Each substation, therefore, is supplied with the contact-making voltmeter 44 which, as will be hereinafter fully explained, is instrumental in maintaining the voltages constant that are impressed by the substations upon the trolley conductor.

In addition to maintaining the voltages constant, irrespective of the position of the moving vehicle 5 or other power demands from the substations 3 and 4, the oppositely directed currents flowing to the moving vehicle 5 must be substantially opposed in phase relationship in order to effectively neutralize the inductive electromotive forces in the conductor 6. To this end, the substations are supplied with the contact-making power-factor relays 55 which insure that the currents flowing from the immediately adjacent substations that are connected through the pilot conductors 65 shall be maintained in substantial phase opposition to each other, under all load conditions.

Referring again to the function of the booster generators 14 and 15, in conjunction with their auxiliary control apparatus, it is apparent that the booster generator 14 may generate an electromotive force that is either substantially in phase with, or in direct phase opposition to, the electromotive force generated in the secondary winding 11 of the power transformer 9. This is apparent since the associated excited winding 22 of the booster generator 14 is impressed with the same voltage that excites the primary winding 10 of the power transformer 9. By means of the adjustable rheostat 25, the direction of flow, as well as the value of, current through the exciting winding 22, is controlled. The booster generator 15, by reason of its exciting winding 41 being supplied with current from the phase 31 of the two-phase supply circuit, may generate electromotive forces that are substantially at right angles to those generated by the booster alternator 14. In a similar fashion, the adjustable rheostat 25 controls the direction of flow, as well as the value of the current traversing the exciting winding 41.

It is, therefore, obvious that the booster alternators 14 and 15 are capable of supplying component electromotive forces that are displaced 90° from each other and that, by adjusting the values of these generated electromotive forces, the value of the resultant electromotive force, that may be combined with the electromotive force generated in the secondary winding 11 of the power transformer 9, may be controlled. As a consequence thereof, the voltage impressed upon the railway circuit may be the resultant of

three component voltages, namely, that of the secondary winding 11 of the power transformer 9, that of the booster generator 14 and that of the booster generator 15.

Reference may now be had to Fig. 2, in which a vector OA may represent, in length and position, the value and phase of the voltage, as well as the current that it is desired for one of the substations to respectively impress upon, and to supply to, the trolley conductor 1. Assume, for instance, that a vector OB represents, in value and phase, the voltage which may be momentarily impressed by this substation by reason of the load distribution upon the railway circuit. In order that the voltage vector OB may coincide with the voltage vector OA, a voltage vector BA is vectorially subtracted from the former. The vector BA, in turn, comprises two components BC and CA, the vector BC being dependent upon the power factor or phase position of the vector OB. The component vector CA, which is proportional to the excess value of the vector OB, may be considered as being generated by the booster generator 14, and the voltage component vector BC, which is proportional to the phase displacement of the vector OB relative to the vector OA, may be considered as being generated by the booster alternator 15. Since the booster alternators 14 and 15 are mounted upon a common shaft and develop electromotive forces of the same frequency, the vector OB is so modified as to coincide, in phase and value, with the vector OA.

The same reasoning may be applied to a vector OD which is substantially smaller in length than the vector OA, as well as being displaced in phase therefrom. When this circumstance obtains, however, the booster alternators 14 and 15 will respectively generate voltages, the directions of which are reversed with reference to the voltages generated by them in the case mentioned above. A component vector EA, generated by the booster alternator 14, and a component vector ED, generated by the booster alternator 15, conjointly modify the voltage vector OD, so that it will coincide in value and phase relationship with the voltage vector OA. By reason of this control of the voltages impressed upon the railway system by the substations, and, consequently the control of the power currents supplied therefrom, the control devices hereinbefore described are instrumental in maintaining the oppositely directed power currents in exact phase opposition.

While the phase 7 of the two-phase supply circuit 8 is shown as furnishing all the power currents to the railway system, it will be understood that it is usually preferable that the several phases of the polyphase distributing circuit be maintained in bal-

anced condition. This may be obtained by properly distributing the load circuits in order to equalize the loads impressed upon the separate phases or by supplying the 5 polyphase circuit with a phase balancer of any usual type, by means of which the loads of the several phases may be equalized.

While I have shown one embodiment of my invention, it will be understood that 10 many modifications may be made therein without departing from the spirit and scope of the appended claims.

I claim as my invention:

1. In an alternating-current distributing 15 system, the combination with a single-phase alternating-current power circuit, of a plurality of spaced power units for furnishing energy to said power circuit, translating devices adapted to draw energy from variable 20 points in said power circuit between said power-unit connections thereto, single-phase commutator-type generators connected in series with said power circuit and severally generating electromotive forces that are displaced 25 90° in phase from each other, and means for independently varying the electromotive forces of said commutator-type generators in order that the voltage impressed upon said power circuit may be 30 maintained at a predetermined value irrespective of the position of said translating devices between said power-supply units.

2. In an alternating-current distributing 35 system, the combination with a single-phase alternating-current power circuit, of a plurality of spaced power units for furnishing energy to said power circuit, translating devices adapted to draw energy from variable 40 points in said power circuit between said power-unit connections thereto, single-phase commutator-type generators connected in series with said power circuit and severally generating electromotive forces that are displaced 90° in phase from each other, means

comprising an adjustable rheostat for independently controlling the direction and amount of current flow through the exciting windings of said generators, and relay mechanism so adjusted that said rheostat is operative only when the power currents supplied by adjacent power stations depart from substantial phase opposition, whereby the voltage impressed upon said power circuit may be maintained at a predetermined value irrespective of the position of said translating device between said power-supply units. 45 50 55

3. In an alternating-current distributing system, the combination with a single-phase alternating-current power circuit, of a plurality of spaced power units for furnishing energy to said power circuit, translating devices adapted to draw energy from variable points in said power circuit between said power-unit connections thereto, single-phase commutator-type generators connected in series with said power circuit and severally generating electromotive forces that are displaced 90° in phase from each other, means comprising an adjustable rheostat for independently controlling the direction and amount of current flow through the exciting windings of said generators, and relay mechanism associating said power circuit and said rheostat whereby said rheostat is adjusted in one direction or the other as dictated by the departure of the currents furnished by adjacent power stations from substantial phase opposition, in one direction or the other, whereby the voltage impressed upon said power circuit may be maintained at a predetermined value irrespective of the position of said translating devices between said power-supply units. 60 65 70 75 80

In testimony whereof I have hereunto 85 subscribed my name this 10th day of Sept. 1917.

CHARLES LE G. FORTESCUE.
